MAGNETO-DIFFERENTIAL TAKE-UP MECHANISM

Carl F. von Wehrden, Honolulu, Territory of Hawaii

Application December 9, 1953, Serial No. 397,277

7 Claims. (Cl. 242—75.51)

(Granted under Title 35, U. S. Code (1952), sec. 266)

The invention described herein may be manufactured and used by or for the Government for governmental purposes, without payment to me of any royalty thereon.

This invention relates to a mechanism for supplying a varying torque from a fixed torque source, and, more particularly, to a magneto differential take-up device which insures a constant rate of travel and application of a uniform tension to material being wound or reeled, such as film, tape, thread, or wire. For example, in the winding and reeling of moving picture film with a sound track, the film must be wound at a uniform rate for proper sound reproduction. When winding film or other material, the effective winding diameter of the film on the reel builds up, resulting in a non-uniform winding rate which restrains the winding reel from rotating at the proper speed. The device of the instant invention drives the winding reel at an R. P. M. sufficient to maintain a constant tension when the film is supplied to the winding reel at a uniform rate of travel regardless of the winding diameter and other factors which would tend to vary the tension in the film.

Devices heretofore used to maintain constant tension in material supplied to a winding reel at a uniform lineal velocity have included magnetic brakes, friction clutches, slipping belts, and more recently torque motors. Generally, in winding and reeling of material, control of lineal velocity and tension are obtained by braking means. The instant invention concerns a tractive device rather than a restraining device, as film or other material is fed to the reeling apparatus rather than being drawn from it, and the present construction is in effect a simplified version of a torque motor that is driven mechanically rather than by a source of external electric power, and may be used in conjunction with winding and reeling apparatus to maintain constant tension when material being wound or reeled is supplied to the reel at a uniform lineal velocity. The instant invention was developed for use in connection with film spool-drives, but may be applied to other material being wound or reeled such as tape, thread, and wire, where constant tension for material supplied to a winding reel at a uniform rate of travel is of paramount importance. Experience has indicated that torque motors, while providing improved operation, for example, of film spool drives, do not afford the constant tension that is essential with film carrying a sound track being reeled at a uniform lineal velocity to provide proper sound reproduction. The devices presently in use do not entirely eliminate the difficulties resulting from improper tension such as film damage, improper sound reproduction and worn sprockets arising from the use of the present troublesome friction devices. It is therefore a primary object of the present invention to provide an improved device for use in connection with winding and reeling equipment which will maintain constant tension of material being wound or reeled continuously at uniform lineal velocity during the winding or reeling operation.

It is a further object of the present invention to provide

2

a device for maintaining constant tension of material being reeled at a uniform lineal velocity wherein the device is controlled by the difference of two speeds, one a constant speed driven member constituting a part of the device and a variable speed reeling member.

It is a further object of the present invention to provide a differential gear train with an input element, an output element, and a magnetically controlled third element for maintaining constant tension of material being reeled or wound at uniform lineal velocity.

It is a further object of the present invention to provide a magneto-differential take-up device which does not require adjustment and does not depend on the use of friction surfaces or springs for maintaining constant tension of material being reeled or wound at constant lineal velocity.

It is a further object of the present invention to provide a device for continually maintaining uniformity of tension of material being reeled at constant lineal velocity, the operation of which is not affected by splashing lubricants, does not require frequent cleaning, is not subject to rapid wear, and is simple to install.

It is a further object of the present invention to provide a device for maintaining constant tension of material being reeled at constant lineal velocity, which device can be mounted co-axially with the reeling member.

It is an additional object of the present invention to provide a magneto-differential take-up mechanism for maintaining constant tension of material being reeled at constant lineal velocity wherein said mechanism is not directly connected to an external electrical source and the reel and material being reeled are not common with said take-up mechanism.

It is a further object of the present invention to provide a magneto-differential take-up mechanism for reeling operations wherein said take-up mechanism continuously applies a torque to the reeling apparatus which is proportional to the winding diameter of the reel for driving said reel to maintain constant tension of the material being reeled at constant lineal velocity.

It is a still further object of the present invention to provide a magneto-differential take-up device for reeling apparatus wherein said take-up device applies a torque differential to said reeling apparatus which tends to drive the reeling apparatus at a speed of rotation sufficient to overcome the speed reduction incurred by the increasing winding diameter of the reeled material and constantly maintain a speed of rotation of said reeling apparatus to insure constant tension of the material being reeled at constant lineal velocity.

Further objects and advantages will become apparent and the invention will be better understood from the following description taken in connection with the accompanying drawings in which—

Fig. 1 is a view in elevation of a particular embodiment of the instant invention showing a magneto-differential take-up mechanism employing one method of differential gearing for connecting the driving source through a magnetic drive assembly to the reeling apparatus;

Fig. 2 is a partial left end elevational view of Fig. 1;

Fig. 8 is a view, partly in section, of a further embodiment of the invention wherein the driving source and magnetic drive assembly are coaxially arranged with the driven reeling apparatus, and

Fig. 9 is a view, partly in section, of another embodiment of the invention employing a differential gearing arrangement with external contact connecting the drive source to the reeling apparatus through another form of magnetic drive assembly.

Referring now to Fig. 1, there is shown one embodiment of the instant invention wherein the components constituting the magneto-differential take-up mechanism are mounted at one end of a shaft 1 supported in a sleeve 2 which is in turn held by a support 3 of any convenient design. The sleeve 2 is prevented from rotating in the support 3 by set screws 4. A collar 5 is secured by set screw 6 to the shaft 1 at the end opposite the take-up mechanism and prevents excessive lateral motion of the shaft. A reel or other similar winding member 7 to which material 7' to be reeled is supplied at a uniform lineal velocity is mounted on the shaft 1 at the end opposite that mounting the take-up mechanism between the collar 5 and a latch 8 which in cooperation with a spring member 9 retains the reel or winding member 7 in position on the shaft 1. A combination of a pulley 11 and internal gear 12 formed integrally therewith is arranged for free rotation on shaft 1. A torque arm 13 eccentrically mounted is secured to shaft 1 by means of a set screw 14 adjacent to the internal gear portion of the combined pulley and internal gear structure. The arm 13 has formed integral therewith at one outermost end a portion 10 which is upstanding with relation to the plane of the arm 13, which portion has a bore 15 therethrough at right angles to the plane of the arm 13 for receiving a shaft 16 which is parallel to shaft 1. The shaft 16 which protrudes beyond the bore 15 has a pinion gear 17 secured at one end thereof for contact with the internal gear 12. The opposite end of the shaft 16 which also protrudes beyond the bore 15 carries a mounting plate 18 having mounting studs 19 located on the outer plane surface thereof. A cup-shaped member 20 of non-ferrous metal such as aluminum, having a central aperture 21 and apertures 22 mutually spaced from the central aperture 21, arranged for registering relation with the aforesaid mounting studs 19, is secured to the mounting plate 18 by seating on the studs 19 and bolt 23 engaging an internally threaded portion in the outer end of the shaft 16 and coaxial therewith. Two L-shaped permanent magnet members 24, 25 are also secured by the shorter legs of the L-shaped members to the arm 13 as by bolts 27, so as to provide an air gap 26 between the longer legs of the L-shaped members which are parallel to the plane of the arm 13. When so mounted, a portion of the arm 13 forms a yoke for the permanent magnet members. The upstanding portion of the cup-shaped member 20 is arranged to pass through the magnetic field in the air gap 26 when the cup-shaped member is rotated.

When the device is operating, the pulley 11 and the integral internal gear 12, which combination is free to rotate on shaft 1, are driven at constant speed from an external source. Internal gear 12 meshes with pinion gear 17 which is connected through the shaft 16 to the cup-shaped member 20. If no retarding torque is applied to the shaft 16 by the cup-shaped member 20, pinion gear 17, shaft 16, and the cup-shaped member 20 rotate in a fixed position in accordance with the ratio of internal gear 12 and pinion gear 17. However, since the non-ferrous cup-shaped member 20 passes through the magnetic field in air gap 26 between the permanent mag-

net legs 24 and 25, eddy currents are generated in the cup-shaped member which produce a magnetic field opposing the magnetic field of the permanent magnet structure, thereby retarding rotation of the cup-shaped member 20, causing the cup-shaped member 20, shaft 16, and pinion gear 17 in addition to rotating to travel along internal gear 12 at a speed of revolution proportional to the retarding torque applied to shaft 16 by cup-shaped member 20. Rotation of pinion gear 17 along internal gear 12 causes the shaft 1 to be rotated by rotational force applied by the arm 13 which revolves about a longitudinal axis through shaft 1 to which the arm 13 is secured. Since the arm 13 is fastened to the shaft 1, rotational force is applied to the reel 7 attached thereto. If a retarding force sufficient to stop the cup-shaped member 20 were applied by virtue of the opposing magnetic field resulting from the self-generated eddy currents, shaft 16 and pinion gear 17 would be prevented from rotating about the axis of shaft 16, and being thus restrained in a fixed meshed position, pinion gear 17 and arm 13 would be rotated at the same speed as the pulley 11 and integral internal gear 12. Reel 7 connected to arm 13 through shaft 1 would therefore also rotate at the same speed as the combination of pulley 11 and internal gear 12. In the practical application of the instant invention, the arm 13 is restrained from rotating as fast as the assembly of pulley 11 and internal gear 12 by the film or other material 7' being reeled. The arm 13 thus rotates at a lower lineal velocity than that of a point on the pitch diameter of internal gear 12. The speed of rotation of the combined assembly of pulley 11 and internal gear 12, which is constant, must be greater than the maximum speed of shaft 1 and the parts attached thereto to overcome the friction of the moving parts which occurs at the minimum winding diameter of the material being spooled. There is always an overdrive and this speed differential increases as the winding diameter increases and the reel 7 slows down. The speed of the shaft 1 will therefore be controlled by the speed and effective winding diameter of the material 7' on the reel 7 carried by the shaft 1. As the reel 7 fills with material 7', at a constant lineal velocity, the effective winding diameter will increase and the rotation speed of shaft 1 and arm 13, attached thereto, will slow down, causing an increase in the speed of pinion gear 17 and cup-shaped member 20. The increased speed of rotation of the cup-shaped member 20 through the flux in the magnetic air gap 26 increases the eddy currents generated therein and consequently greater opposition to the magnetic field in the permanent magnet structure results, tending to retard the rotation of the member 20, which in turn causes increased torque to be exerted on arm 13 and shaft 1 in a manner previously described, which increase in torque is required to balance the longer lever arm of the material 7' at the larger winding diameter on the reel 7 on shaft 1. The increase in speed of member 20 and consequent increase in torque is proportional to the increase in winding diameter of material 7', and consequently constant tension will result for the winding of an entire reel of material.

The structure shown in Fig. 5 operates on the same principle as the structure shown in Figs. 1 and 3 but is a more compact coaxial arrangement employing another form of differential gearing and permanent magnet structure, a portion of which serves as an end closure for the unit. The shaft 1 and reel 7 are supported in the same manner as shown for the embodiment illustrated in Figs. 1 and 3. The combined assembly of pulley 11 and internal gear 12 has a slightly different configuration and includes a portion 28 which joins the pulley 11 to the internal gear 12 and forms a cavity 29. A circular band 30 of non-magnetic material is secured to a portion of the exterior surface of the combined assembly of pulley 11 and internal gear 12 by bolts 31 so as to form an extension thereof which is flush with the exterior sur-

face of the combined assembly and coaxial with the shaft 1. A cup-shaped permanent magnet structure 32 having an upstanding portion 33 located centrally of the bight portion thereof, is joined to the combined assembly of pulley 11 and internal gear 12 by the circular band 30 by bolts 31 with the flange of the cup-shaped magnet member facing the combined assembly so that the permanent magnet structure 32 forms a closure for the unit. A cruciform pole member 34 of permanent magnetic material is integral with the upstanding portion 33, at right angles thereto, with the flange of the cup-shaped magnet structure 32 surrounding the arms of the cruciform pole member 34. The arms of the member 34 are slightly shorter in length than the diameter of the flange so as to form an air gap 35 therebetween. An arm 36 is eccentrically secured to shaft 1 and positioned within the cavity 29. The arm 36 has an aperture 78 therethrough in a direction at right angles to the length of the arm to receive a stub shaft 37 secured by set screw 38 which extends for a distance in the direction of the internal gear 12 sufficient to permit mounting a planet gear 39 by means of a bolt and washer assembly 45 so as to mesh with internal gear 12. A cup-shaped member 40, having a central tubular portion 41 integral therewith for slip-fitting on the shaft 1 is secured thereto adjacent to the end thereof extending toward the cruciform member 34 by bolt 42 and washer 43 in such manner that the upturned portion of the cup-shaped member 40 may pass through the air gap 35. The cup-shaped member 40 is connected to the planet gear 39 through a sun gear 44 carried by shaft 1 between the arm 36 and cup-shaped member 40. Sun gear 44 may be separate or integral with cup-shaped member 40.

The operating principle of the modification shown in Figs. 5, 6 and 7 is similar to that shown in Figs. 1, 2, 3 and 4. When the combined assembly of pulley 11, internal gear 12 and the permanent magnet assembly mounted for free rotation on shaft 1, are driven by an external source and the shaft 1 is restrained from rotating, the planet gear 39 will revolve and in turn rotate the sun gear 44 and the cup-shaped member 40 through the magnetic field in the air gap 35. The opposing magnetic field set up by the eddy currents thus generated in the cup-shaped member 40 will retard the rotation of member 40, sun gear 44 and planet gear 39 causing a torque to be applied to the arm 36. The torque so developed will vary with the speed at which shaft 1 is allowed to rotate. For example, when shaft 1 is prevented from rotating, maximum torque is developed, and when the revolutions per minute of shaft 1 equal the revolutions of the combined assembly of pulley 11 and internal gear 12, no torque will be developed. For intermediate values of revolutions per minute of shaft 1, the amount of torque developed will be in proportion to the difference in speeds of shaft 1 and the combined assembly of pulley 11, internal gear 12 and the permanent magnet assembly. The speed of shaft 1 is controlled by the lineal speed of the material 7' being spooled and the winding diameter. The difference in speeds between the combined assembly and shaft 1 is multiplied by the gear train or other mechanical equivalents such as sprockets and chains and rubber drive wheels to rotate the cup-shaped member 40 through the magnetic field at sufficient speed to produce the necessary torque driving shaft 1 to produce the required tension in the material 7' being spooled.

The modification shown in Figs. 5, 6, and 7 is likewise applicable to winding material such as tape, film, wire, and thread at constant tension and uses the variation in winding diameter of the material 7' to regulate the change in torque necessary to provide constant tension for the material being reeled at uniform lineal velocity.

There is illustrated in Fig. 8 a further embodiment of 75 velocity relative to the combined pulley, internal gear

the device of the instant invention wherein the components are coaxially arranged and the relative position of the combined internal gear and pulley, and the permanent magnet and cup-shaped non-magnetic member are reversed. In this arrangement the unit is composed of individual separate components and the cup-shaped non-magnetic member forms the end closure member for the unit. The support for the unit and the reel is similar to that illustrated in the previous embodiments and are designated by corresponding reference numbers. A pulley 45 is carried by shaft 1 for free rotation thereon at the end opposite the reel 7 and adjacent the sleeve 2. A circular band 30 similar to that used in the embodiment illustrated in Fig. 5 joins the pulley 45 and a cup-shaped permanent magnet structure 46 in mutually spaced relation. The magnet structure 46 has an aperture 47 centrally located on the bight portion thereof and upstanding portions 48 located intermediate the flange 49 of said cup-shaped member and said central aperture 47. A permanent magnet pole member 50, which may be any convenient shape, is secured to the upstanding portions 48 by bolts 50'. The magnet member 50 is slightly less in length than the diameter of the flange 49 thereby providing an air gap 51 in the magnetic circuit. The pole member 50 has a central aperture 57. A cup-shaped member 54, the vertical side portions of which form an internal gear 52, is arranged intermediate the pulley 45 and permanent magnet structure 46 with the internal gear facing the pulley and forming a cavity 53 therebetween. The cup-shaped member 54 has a central aperture 56 and is secured by bolts 55 through the base thereof to the bight portion of the permanent magnet structure 46. The pulley 45, internal gear 54 and permanent magnet structure 46 are of the same diameter and the apertures 47, 56, and 57 are axially aligned and coincident with the longitudinal axis of shaft 1. A shaft 58 passes through the aligned apertures 47, 56, and 57 and protrudes beyond the apertures 56 and 57 to permit mounting a sun gear 59 on the end 40 within the cavity 53 and a mounting plate 60 on the end protruding beyond the aperture 57. The mounting plate 60 has a central aperture 61 and a plurality of mounting studs 62 surrounding the central aperture 61 and mutually spaced therefrom. A cup-shaped non-magnetic member 63 having a central aperture 64 surrounded by mutually spaced apertures 65 which are in registering relation with the mounting studs 62, is mounted thereon and secured to the shaft 58 by a bolt 66 so that the upstanding portion of the cup is free to rotate through the magnetic field in air gap 51. An arm 67 is eccentrically secured to the shaft 1 within the portion of the cavity 53 formed by pulley 45. The arm 67 has an aperture 68 therethrough in a direction at right angles to the length of the arm to receive a stub shaft 69 secured by set screw 70. The stub shaft 69 extends toward the internal gear 52 an amount sufficient to permit mounting a planet gear 71 by bolt and washer assembly 72 for meshing relation with the internal gear 52. Sun gear 59, carried by shaft 58, meshes with planet gear 71. The operation of the modified form of the invention illustrated in Fig. 8 is similar in principle to that of the previously described forms. An external drive source connected to pulley 45 rotates the combined assembly of pulley 45, internal gear 52 and the entire permanent magnet assembly freely on shaft 1. Rotation of the internal gear 52 causes planet gear 71 to be rotated which in turn drives the sun gear 59 and the cup-shaped non-magnetic member 63, carried on the same shaft 58, through the magnetic field existing in the air gap 51. The differential gearing arrangement provides relative rotation between the combination of pulley 45, internal gear 52, the complete permanent magnet assembly and the non-magnetic cup-shaped member 63 which rotates at a higher

and permanent magnet assembly. Rotation of the cup-shaped member 63 through the magnetic field in the air gap 51 induces eddy currents in the cup-shaped member, retarding the rotation thereof as previously explained, which in turn results in the application of a torque to the arm 67 and through shaft 1 to the reel 7 which results in constant tension of the material 7' being reeled at uniform lineal velocity. The torque developed will be in proportion to the difference in speeds of shaft 1 and combination of pulley, internal gear and permanent magnet assembly. The same relations exist with regard to winding diameter, speed of shaft 1, lineal velocity of material 7' being spooled and speed of the combined assembly of pulley and internal gear, differential gearing, cup-shaped member and permanent magnet assembly for the modification illustrated in Fig. 8 as for the forms of the invention previously described.

A further modification of the invention is illustrated in Fig. 9 which differs from the previous forms in that an external gear and permanent magnet structure is used wherein the torque arm is a part of the permanent magnet structure. The support structure for the form illustrated in Fig. 9 is similar to that used in the embodiments previously described and corresponding parts have been designated by like reference characters. A pulley 73, having combined therewith in an integral structure an external gear 74, is mounted for free rotation on one end of the shaft 75 which extends beyond the support sleeve 2. Mounted on the same end of shaft 75 on the outer end portion thereof and adjacent the combination of pulley 73 and external gear 74 is a U-shaped member 76 formed from sheet material, having legs of unequal length. A cup-shaped permanent magnet 97 having a central upstanding portion 77 is secured by any convenient means to the internal side of the longer leg 79 of the U-shaped member 76. The central upstanding portion 77 has a bore 80 longitudinally thereof and the longer leg 79 of the U-shaped member 76 is provided with an aperture 81 in registering relation with the bore 80 for securing the combination of U-shaped member and cup-shaped permanent magnet structure 97 on shaft 75 by a set screw 82. Secured to the inside surface of the shorter outside leg 83 of the U-shaped member 76 by any convenient means is a permanent magnet member 84, which being mutually spaced from the cup-shaped permanent magnet structure forms an air gap 85 therewith. The longer leg 79 of the U-shaped member 76 has an upstanding portion 98 of substantial diameter facing inwardly of the leg 79 with a bore 86 therethrough. The axis of the bore 86 is at right angles to the plane of the longer leg 79 and parallel to the axis of the shaft 75. A stub shaft 87 is carried within the bore 86 and extends a distance beyond each end of the bore to permit mounting a pinion gear 88 at the end adjacent the external gear 74 in meshing relation therewith and a mounting hub 89 having a central bore 90 for mounting on said stub shaft 87 at the end opposite said pinion gear 88. A plurality of mounting studs 91 protruding beyond the outer planar surface of the mounting hub are arranged in surrounding mutually spaced relation from said central bore 90. The stub shaft 87 has an internally threaded, longitudinal recess 96 centrally located. A disk 92 of non-magnetic material having a central aperture 93 and surrounding adjacent mutually spaced apertures 94 in registering relation with said protruding studs 91 for mounting said disk 92 on stub shaft 87. The disk is further held in position on stub shaft 87 by a bolt 95 engaging the internally threaded recess 96. The disk 92 is of sufficient diameter to insure passing through the magnetic field in the air gap 85 between the mutually spaced permanent magnet members of the magnetic circuit.

The operation of the embodiment shown in Fig. 9 is also similar in principle to the embodiments previously described. An external drive source is connected to the 76

combination pulley 73 and external gear 74 thereby rotating the pulley which in turn drives pinion gear 88 and disc 92. As the disc 92 is rotated through the magnetic flux in the air gap 85, eddy currents are induced therein which tend to retard the disc causing a torque, proportional to the difference in speeds of shaft 75 and combination assembly of pulley 73 and external gear 74, to be applied to the shaft 75 and reel 7 attached thereto by a latch 8 which in cooperation with a spring member 9 retains the reel or winding member 7 in position on shaft 1. The torque arm in this embodiment is the longer leg 79 of the U-shaped member 76. The same relations with regard to winding diameter, speed of shaft 75, lineal velocity of material 7' being spooled and speed of the combined assembly of pulley, external gear, permanent magnet and attached U-shaped member for the embodiment illustrated in Fig. 9 as for the preceding embodiments.

From the foregoing description it is evident that the instant invention provides a simple, compact structure employing a principle of operation which insures constant tension for material such as tape, thread, wire, and film being reeled at uniform lineal velocity wherein the tension is controlled by the material being reeled. The principle involved may be applied in a variety of embodiments of which those described are representative.

Having thus described my invention, what I claim as new and wish to secure by Letters Patent is:

1. A magneto-differential take-up assembly for reeling apparatus comprising support means, a shaft carried by said support means for free rotation therein, said shaft extending in opposite directions beyond said support means, a reel, an input element, said reel mounted in fixed position on an extending end of said shaft, said input element mounted for free rotation on said shaft in mutually spaced relation with said reel, eddy current generating means, differential drive means connected to said input element, torque applying means secured to said shaft and coupling said eddy current generating means to said differential drive means whereby upon retardation of said eddy current generating means responsive to variations in velocity of said shaft relative to said input element force is applied to through said torque applying means to said shaft effective to maintain constant tension in material being wound on said reel at uniform lineal velocity.

2. A magneto-differential take-up assembly for reeling apparatus comprising support means, a main shaft carried by said support means for free rotation therein, said main shaft extending in opposite directions beyond said support means, a reel secured to one extending end of said main shaft, a pulley mounted for free rotation on said main shaft in mutually spaced relation with said reel, an internal gear integral with said pulley, a torque arm secured to said main shaft adjacent said internal gear in face relation therewith, a pinion gear, a stub shaft carried by said torque arm parallel to said main shaft, said pinion gear secured to said stub shaft for maintaining said pinion gear in meshing relation with said internal gear, a pair of elongated permanent magnet members secured to said torque arm and extending in a direction parallel to the length of said torque arm, said magnet members arranged in mutually spaced relation to form a magnetic path, a non-magnetic cup-shaped member secured to said stub shaft to permit rotation through said magnetic path, said pulley, torque arm, permanent magnet members and cup-shaped member arranged in lateral mutually spaced relation with said cup-shaped member and cooperating to apply a force to said torque arm dependent upon the velocity of said pulley relative to said cup-shaped member whereby said main shaft and attached reel are driven to maintain constant tension of material being reeled at uniform lineal velocity when said pulley is driven at constant velocity.

3. In combination with a reeling apparatus, a magneto-

differential take-up mechanism for maintaining constant tension of material being reeled at uniform lineal velocity comprising a support, a main shaft carried by said support for free rotation therein, said main shaft extending in opposite directions beyond said support, pulley means mounted for free rotation on one extending end of said main shaft, internal gear means formed integral with said pulley means, cup-shaped permanent magnet means having a planar base portion, means connecting said permanent magnet means to said pulley and internal gear means in coaxial registering relation, said cup-shaped magnet means having a central portion perpendicular to the planar base portion thereof, a magnetic pole structure formed integral with said perpendicular portion at right angles thereto within said cup-shaped magnet means, said pole structure being of lesser diameter than said cup-shaped magnet member thereby forming a magnetic field therebetween, said cup-shaped magnet means and said pulley means being mutually spaced to provide a cavity therebetween, said pulley means and said cup-shaped magnet means cooperating to form closure means for said mechanism, torque applying means secured to said main shaft within the portion of the cavity formed by said pulley means, a stub shaft carried by said torque applying means, a planet gear carried by said stub shaft for meshing relation with said internal gear means, a sun gear mounted on said main shaft in meshing relation with said planet gear, a cup-shaped non-magnetic member carried on said main shaft for rotation through said magnetic field and responsive to variations in velocity of said main shaft whereby retardation of said cup-shaped non-magnetic member relative to said pulley means applies a force to said torque applying means through said planet and sun gears for rotating said main shaft to maintain constant tension in material being reeled at uniform lineal velocity when said pulley means is driven at constant velocity.

4. A magneto-differential torque motor for maintaining constant tension of material being reeled at uniform lineal velocity, comprising a support, a main shaft carried by said support for free rotation therein, said main shaft extending in opposite directions beyond said support, means externally driven and mounted for free rotation on said main shaft on one extending end of said main shaft, a cup-shaped permanent magnet structure having a planar base portion and a flange portion perpendicular thereto, means connecting said externally driven means to the planar base portion of said cup-shaped permanent magnet structure in mutually spaced coaxial registering relation, a differential gear train assembly located between said externally driven means and said cup-shaped permanent magnet structure and secured to said permanent magnet structure for cooperative simultaneous rotation therewith, a second shaft, said cup-shaped permanent magnet structure having a central aperture, an upstanding portion located intermediate the flange portion of said cup-shaped magnet structure and said central aperture, a pole piece carried by said upstanding portion positioned within the flange of said cup-shaped magnet structure adjacent the outer rim thereof, said pole piece being of lesser diameter than said cup-shaped magnet structure forming a magnetic path therebetween, said pole piece and said differential gear train assembly each having a central aperture in registering relation with the central aperture in said cup-shaped magnet structure to receive said second shaft in longitudinal coaxial alignment with said main shaft, a cup-shaped non-magnetic member carried by said second shaft for rotation through said magnetic path, torque applying means secured to said main shaft and coupled to said cup-shaped non-magnetic member through said differential gear train assembly for relative rotation therewith, said cup-shaped non-magnetic member responding to variations in velocity of said main shaft relative to said externally driven means, whereby retardation of said cup-shaped non-magnetic member im-

poses a force on said torque applying means through said differential gear train assembly to said main shaft to maintain constant tension of material being reeled at uniform lineal velocity when said externally driven means is rotated at constant velocity.

5. A magneto-differential torque motor for maintaining constant tension of material being reeled at uniform lineal velocity, comprising a support, a main shaft carried by said support for free rotation therein, said main shaft extending in opposite directions beyond said support, pulley means carried by said main shaft for free rotation thereon, external gear means integral with said pulley means and in lateral coaxial relation therewith, a U-shaped member having legs of unequal length and substantial width, the longer leg of said U-shaped member being apertured to permit supporting said U-shaped member on said main shaft in adjacent relation to said external gear, a cup-shaped permanent magnet structure having a central upstanding portion secured to the inner side of the longer leg of said U-shaped member and adapted to be supported by said main shaft in fixed relation thereto, the shorter leg of said U-shaped member being free of said main shaft and arranged in mutually spaced face relation with said cup-shaped magnet structure, a disc-shaped permanent magnet structure secured to the internal surface of the shorter leg of said U-shaped member in mutually spaced face relation with said cup-shaped magnet structure forming a magnetic path therebetween, an upstanding portion having a bore therethrough formed integral with the longer leg of said U-shaped member adjacent the end thereof and perpendicular thereto, a stub shaft carried within said bore parallel to said main shaft and extending a substantial distance beyond said bore, a pinion gear carried by said stub shaft in meshing relation with said external gear, a non-magnetic disc carried by said stub shaft in opposed relation to said pinion gear for rotation through said magnetic path, said disc being responsive to variations in velocity of said main shaft relative to said pulley means whereby retardation of said disc imposes a force on the longer leg of said U-shaped member effective to rotate said main shaft to maintain constant tension of material being reeled at uniform lineal velocity when said pulley means is driven at constant velocity.

45. A device for regulating reeling apparatus to maintain constant tension of material being reeled at uniform lineal velocity comprising a shaft, support means for said shaft, input means mounted for free rotation on said shaft, said input means being driven at constant angular velocity, a reel mounted adjacent an end of said shaft for rotation therewith and remote from said input means, an arm eccentrically secured to said shaft adjacent said input means for rotation in a plane normal to the axis of said shaft, mechanical coupling means coacting with said arm and interconnecting said input means and said shaft, permanent magnet means including an air gap mounted for rotation about said shaft adjacent said input means and electrical conducting means connected to said mechanical coupling means and rotated through said air gap upon rotation of said input means, rotation of said conducting means through said air gap inducing eddy currents therein opposing the magnetic flux in said air gap and retarding the rotation of said conducting means whereby a varying torque is applied through said arm to said shaft to maintain uniform tension with varying winding diameter of material wound on said reel at constant lineal velocity.

7. A device for maintaining constant tension in material being reeled at uniform lineal velocity comprising a shaft, support means for said shaft, input means mounted for free rotation on said shaft, said input means being driven at constant velocity, a reel mounted adjacent an end of said shaft for rotation therewith and remote from said input means, an arm eccentrically secured to said shaft adjacent said input means for rotation in a plane

normal to the axis of said shaft, differential drive means coaxing with said arm and interconnecting said input means and said shaft, said differential drive means and said shaft having a common center of rotation, permanent magnet means including an air gap supported coaxially by said input means for free rotation about said shaft, electrical conducting means supported by said shaft for rotation through said air gap simultaneously upon rotation of said input means, rotation of said conducting means through said air gap inducing eddy currents therein opposing the magnetic flux in said air gap and retarding the rotation of said conducting means, said electrical conducting means connected to said arm through said differential drive means, whereby upon rotation of said differential drive means about its center of rotation, due to variations in angular velocity of said reel relative to said input means, a varying torque is applied through

said arm to said shaft to maintain uniform tension with varying winding diameter of material wound on said reel at constant lineal velocity.
